TAG

Filed Aug. 20, 1930

UNITED STATES PATENT OFFICE

RICHARD GRAY GALLOGLY, OF MILLEDGEVILLE, GEORGIA

TAG

Application filed August 20, 1930. Serial No. 476,691.

This invention relates to a vehicle license plate intended for permanent use, or for the life of the vehicle to which it may be attached, and has for its object the provision of a tag which is theft-proof but simple and durable in construction. It has a further object of providing a perpetual case or number plate, with the number blanked out, adapted for attachment to the bracket on an automobile, and further adapted for use in conjunction with a replaceable plate situated behind the permanent plate providing both a background for the cut out number and also indicia indicating the State and the license period.

A further object is to provide a method of bolting the permanent plate to a bracket on a vehicle, such as an automobile, in such a manner that the insertion of the replaceable plate will prevent access for the removal of the bolts and hence the removal of the plate from the vehicle.

A further object is to provide a replaceable plate which after once being clamped into position on the permanent case cannot be removed without destroying the plate.

A further object is to produce a license place which is substantially of the same appearance as those now in use but which has a decidedly less tendency to glare.

Other and further objects will be apparent from the following specification wherein there is disclosed a single embodiment of the invention, with the understanding that modifications may be made therein without departing from the spirit of the invention so long as they fall within the scope of the appended claims.

In the drawings:

Figure 1 is a front elevation of the complete tag;

Figure 2 is a rear elevation of the complete tag;

Figure 3 is an elevation on a reduced scale of the replaceable plate as it is intended shall be received from the State license department and prior to its insertion in the permanent plate;

Figure 4 is a vertical section taken on line 4—4 of Fig. 1;

Figure 5 is a horizontal section taken on line 5—5 of Fig. 1;

Figure 6 is a horizontal section taken on line 6—6 of Fig. 1.

Referring to the drawings in detail, the main or permanent case or plate 1 has an upper projecting portion 2 and a number 4 or other indicia which are blanked or cut out. The replaceable plate 3, as best shown in Fig. 3, is slightly smaller in size but substantially of the same shape as plate 1 but has in addition two wings or flaps 5 and 6 having blanked therein or stamped in embossed indicia thereon respectively the year or license period and the name of the State or the abbreviation therefor.

One of the flaps, 5 as shown, has a smaller projecting portion or tab 7, and the other a slot 7a. The two flaps are adapted after insertion of plate 3 behind plate 1 to be bent around the projecting portion 2 of plate 1, the tab 7 to pass through slot 7a, slot 8 of plate 3 and finally through slot 8a of plate 1 to be clamped flat against the back of plate 1.

The flaps 5 and 6 are creased, during their manufacture, at the point of bending as at 14, just deep enough to permit their being folded only one time.

The plate 1 is provided with end portions 9 folded back against the plate but allowing sufficient space for the insertion of plate 3. The end portions 9 are provided with slots 10 adapted to substantially coincide with corresponding slots 11a on the bracket 11 of the automobile. The plate is attached to the bracket by means of a bolt 12 and nut 13 adapted for insertion in slots 10 and 11a. The bolts have slotted heads 12a and are adapted to be tightened by the use of a screw driver inserted through the perforated numerals in plate 1. The nuts 13 are cut to form narrower bases 13a on opposite sides, which, upon tightening, fall in slots 11a of the bracket 11 and thus become sealed or locked and cannot be rotated.

The purpose of the slots 10 and 11a is to permit the lateral movement of the nut and bolt to a point opposite an opening, a numeral or other perforation, which may differ in its position with different numbers, to permit in

sertion of a screw driver for tightening the bolt.

The plate 1 is provided with flaps 1a which prevent the removal of the replaceable plate in an upward direction.

5 The end portions 9, as shown, are triangular in shape and have flanged portions 9a turned inwardly, as illustrated in Figs. 2 and 4 thus preventing access to the heads of the bolts from the back of the plate.

10 Spring lock washers may be placed under the heads of the bolts 12, or any other means may be provided to prevent loosening of the bolts.

15 It is intended that the State license department issue the plate 1 in the same manner in which the present tags are issued, and also that the plate 3 be issued each year in a different color.

20 The permanent plate 1 is preferably made of dull aluminum but may be constructed of any metal or other material and may be painted or unpainted. Dull aluminum is preferable because it is not so likely to glare in sunlight or other light, and is more or less permanent.

25 In attaching the tag to an automobile, the permanent plate 1 is first attached to the bracket of the car. The colored plate is then slipped upwardly from the bottom behind plate 1. The flaps 5 and 6 are then bent around and clamped in the manner previously specified. At the end of the license period or year, the replaceable plate may be easily removed without disturbing the permanent plate and the new plate inserted.

30 It will be noted in the preferred embodiment that all indicia are cut or blanked out and that each plate serves as a background for the indicia in the other plate.

35 Having thus described the invention, what is claimed as new and desired to be secured by Letters Patent is:

40 1. A perpetual license tag comprising a permanent plate having indicia blanked therein, and a replaceable plate constituting a background for said indicia, said permanent plate having means adapted for attaching it to a holder or bracket on a vehicle and said second plate being so positioned as to prevent access to the attaching means, thus preventing removal of said permanent plate from said holder while said second plate is in place.

45 2. A perpetual license plate comprising a permanent plate having indicia blanked therein and a projecting portion, a second replaceable plate constituting a background for said indicia and having projecting wings or flaps provided with indicia describing the State and the license period, adapted to be bent and clamped in position around said projecting portion of said permanent plate.

50 3. A perpetual license plate comprising a permanent plate having indicia blanked

therein and a projecting portion, a second replaceable plate constituting a background for said indicia and having projecting wings or flaps provided with indicia describing the State and the license period, adapted to be 70 bent and clamped in position around said projecting portion of said permanent plate, said second plate being unremovable without its destruction.

4. A perpetual license plate comprising a 75 permanent plate having indicia blanked therein and a projecting portion, a second replaceable plate constituting a background for said indicia and having projecting wings or flaps provided with indicia describing 80 the State and the license period, adapted to be bent and clamped in position around said projecting portion of said permanent plate, said wings or flaps being creased in their manufacture at the point of bending in such 85 a manner as to permit bending but one time.

5. A perpetual automobile license plate comprising a permanent plate having indicia blanked therein and a projecting portion, a second replaceable plate constituting a background for said indicia and having projecting wings or flaps provided with indicia describing the State and the license period, adapted to be bent and clamped in position around said projecting portion of said permanent plate, said permanent plate being adapted for attachment to a holder or bracket on an automobile and said second plate being so positioned as to prevent removal of said permanent plate after attachment to said 100 holder.

6. A duplex license tag comprising a permanent metal plate having a number blanked therein and a replaceable second plate furnishing a background for said number in said 105 first mentioned plate and having indicia indicating the year and State blanked therein on a portion thereof, said portion being lapped over and positioned in front of a portion of said first mentioned plate, whereby said first mentioned plate furnishes a background for the indicia in said second mentioned plate.

7. A theft-proof automobile license tag comprising a permanent plate having indicia blanked therein, means for bolting said plate to a bracket on an automobile, a replaceable plate furnishing a background for said indicia, and further adapted to be inserted in such position as to prevent access to heads of bolts employed in attaching said plate to said bracket, said bolts having lock nuts.

8. In a theft-proof automobile license tag, a permanent plate having indicia blanked therein, means for attaching said plate to a bracket on an automobile only by entrance through said indicia and a second replaceable plate furnishing background for indicia in said first mentioned plate and adapted to prevent access to said attaching means.

9. A perpetual automobile license plate, comprising a permanent metal plate having a number blanked therein and an upper projecting portion, a replaceable plate of a different color than said first mentioned plate adapted to be slipped behind said first mentioned plate to form a background for said number therein, said second plate having two flaps or wing portions adapted to be folded around said upper projecting portion and to be clamped thereto, one of said flaps having stamped therein characters indicating the State and the other the license period, said first mentioned plate having means whereby it may be attached to an automobile comprising slotted portions provided with groove headed bolts and lock nuts, said bolts being in such position that said second plate can be attached or detached only by entrance through the numeral therein and in the absence of said second plate.

In testimony whereof I hereunto affix my signature.
